(57) CLAIM

The ornamental design for a makeup box, as shown and described.

DESCRIPTION

FIG. 1 is a front, right and top perspective view of a makeup box showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of the makeup box, shown in condition of use.

The broken lines in the figures illustrate portions of the makeup box that form no part of the claimed design.
